UNITED STATES PATENT OFFICE.

HARMONEY W. PROULX, OF HOLYOKE, MASSACHUSETTS.

DESIGN FOR A SHOE-STORE SEAT.

SPECIFICATION forming part of Design No. 35,725, dated February 11, 1902.

Application filed December 23, 1901. Serial No. 87,043. Term of patent 7 years.

To all whom it may concern:

Be it known that I, HARMONEY W. PROULX, a citizen of the United States of America, and a resident of Holyoke, in the county of Hampden and State of Massachusetts, have invented and produced a certain new and useful 5 Design for a Shoe-Store Seat, of which the following is a full, clear, and exact description.

Reference is to be had to the accompanying 10 drawings, in which—

Figure 1 is a plan view of the shoe-store seat. Fig. 2 is a side elevation, and Fig. 3 is an end elevation.

As shown in the drawings, the leading 15 characteristic and essential feature of my design consists in the supporting structure comprising the arch A and the arched back B, extended from the middle upper portion of the arch A right angularly to said arch and terminating in the arch-shaped foot B². The 20 arch A, as seen in end elevation, comprises an upper portion *a* of approximately semicircular form, while the extremity of its members *b*, together with said upper portion *a*, 25 are in compound curves or ogees. The right-angularly-extended arched back B curves downwardly and rearwardly from the middle

of the upper portion of the arch A, coming to connection with the small foot-arch B² with increased quickness or sharpness of curvature, 30 and the semicircular foot-arch, as perceived in the edge view thereof, Fig. 2, has a downward and outward curvature, as indicated at *d*. The back arch B near the place of junction of the transverse arch A has an upward 35 circular extension or boss *f*, surmounted by the seat C, of circular form, and the foot-rest D has an inclination forwardly and upwardly relatively to its place of support on the member B. 40

The parts A, B, and *f* are round in cross-section and have "flush" joints, as *g*, *g*², and *g*³, as insured by the one cylindrical part intersecting the other.

Having thus described my invention, what 45 I claim, and desire to secure by Letters Patent, is—

The design for a shoe-store seat, substantially as herein shown and described.

HARMONEY W. PROULX.
